UNITED STATES PATENT OFFICE.

SAMUEL EDWARDS, OF CHARLESTON, WEST VIRGINIA.

RAILWAY TIE AND JOINT.

Application filed October 10, 1924. Serial No. 742,934.

To all whom it may concern:

Be it known that I, SAMUEL EDWARDS, a citizen of the United States, and residing at Charleston, county of Kanawha, State of 5 West Virginia, have invented certain new and useful Improvements in Railway Ties and Joints, of which the following is a specification.

This invention relates to a railway tie 10 adapted to be placed at the point where the ends of two rails are joined, and to rail fastenings to be used in combination with said tie and joint.

It is an object of this invention to provide an improved railway tie of simple and economical construction which has a largely increased bearing surface at the rail joint.

It is a further object of this invention to provide improved rail fastenings adapted to 20 be used with said tie, which will prevent the rails from moving relative to one another or to the tie, and which will maintain the rail ends in proper alignment.

Referring to the accompanying drawings 25 forming a part of this specification:

Figure 1 is a top plan view of my improved tie, showing the rails and rail fastening means thereon;

Figure 2 is an enlarged side elevation of 30 a portion of Figure 1, showing my improved rail joint in detail, and taken on the line 2—2 of Figure 1;

Figure 3 is an end elevation of Figure 1, drawn to the same scale as Figure 2;

Figure 4 is a top plan view, similar to 35 Figure 1, showing only one end of the tie with a modified form of rail fastening means thereon; and

Figure 5 is a sectional elevation of the 40 same, taken on the line 5—5 of Figure 4.

As illustrated in the drawings, my improved tie comprises a central portion 10, and two shorter side portions 11 bolted thereto, one on each side of the central portion 10, and extending slightly beyond the end of the same. For standard gauge construction, the central piece 10 will preferably have the same dimensions as the standard railroad tie, except that it is six inches shorter in length, and the side pieces 11 will be of the same width and thickness as the piece 10, but only half as long. The fact that the piece 10 is six inches shorter than the standard railroad tie makes a substantial saving in the cost of this piece from the mill over the cost of a standard tie, when

obtained in large quantities, and the pieces 11 may be obtained quite cheaply, as they are much shorter in length and may be made from scrap ends of timber which would be 60 totally unsuitable for making into ties. The cost of the entire assembled tie, therefore, is not greatly in excess of that of a single standard tie. It is to be understood, of course, that the pieces 11 will project 65 beyond the central portion the necessary amount, in the above case six inches, to make the overall length of the built-up tie equal to that usually employed. The three pieces of my improved tie are secured together by 70 means of a plurality of transverse bolts 12.

This construction provides a tie having a very large bearing surface at the point where this is most needed, namely, at the joint between two rails. For the sake of 75 economy, only one end of my tie is built up to an increased width, because the width of the standard tie is sufficient where no joint occurs, and, for the same reason, an ordinary standard tie may be used when there 80 is no joint in either rail.

It will be noted that the projecting side portions 11 form between them a notch which permits the trackmen to get at the roadbed to tamp the same firmly under the 85 rail joint, which is a point where the bed endures unusual shocks and therefore requires frequent attention. Moreover, the inner ends of the blocks 11 are square, thus forming shoulders which present a much 90 greater end bearing surface to the roadbed and prevent lateral shifting of the tie after it has been placed in position.

For use with my improved tie, I have devised novel forms of bed plate and splice 95 bars, whereby the rails will be rigidly held together and to the tie. Referring particularly to Figure 2, 13 denotes a bed plate having upturned side flanges 14, and depending end portions 15. The bed plate 13 100 is placed transversely of the tie, and is secured to the tie by means of a bolt 16 passing through the tie and the two end portions 15. The space between the turned down ends 15 is just equal to the width of 105 the tie, so that the bed plate fits snugly over the tie. The base of the rail 17 fits closely between the flanges 14 of the bed plate, which secure the rail against lateral displacement. The flanges 14 are of a height 110 approximately equal to the thickness of the edge of the base of the rails 17, in order not

to interfere with the attachment of the splice bars 18.

The splice bars 18 are each formed, as shown in Figure 2, with a vertical portion 5 which is secured to the web of rail 17 by bolts 19, an inclined portion 20 terminating in a shoulder 21, adapted to fit over the base of the rail and flanges 14, and a horizontal portion 22 ending in a depending flange 23. 10 The flange 23 is adapted to fit in a transverse groove cut in the tie, and the splice bar is provided with holes adjacent the base of shoulder 21, through which spikes 24 are driven into the tie. The splice bars therefore serve the double purpose of fastening the rails together, and securing them to the tie, while the base plate holds the rails in perfect alignment. The depending flanges 23 cooperate with the spikes 24 and the base 15 plate 13 in preventing sideward displacement of the rails, and add additional strength to the unit.

Figures 4 and 5 illustrate a modification of my invention, in which a conventional 20 splice bar and a modified form of bed plate are used. The bed plate 25 is considerably wider than the base of the rail 17, and has portions 26 cut therefrom and bent up to form projections between which the base of 25 the rail is snugly seated. Holes 27 are thus left in the bed plate, through which spikes 24 are driven. The bed plate is provided with depending portions 28 which fit snugly over the tie, and a bolt 29, passing through 30 the end portions 28 and the tie, secures the bed plate firmly to the tie. Splice bars 30, of the conventional type, are bolted to the rails by means of bolts 31.

This modification is somewhat simpler 35 than that shown in Figures 1, 2 and 3, but embodies the same advantages.

A conventional bed plate is illustrated under the left hand rail of Figure 1, but it is to be understood that a bed plate similar 40 to that shown in either Figure 2 or Figure 5 might be employed, the splice bars, of course, being dispensed with, since no joint occurs here.

Many other changes might be made in my 45 invention without affecting the spirit there-

of. For example, the tie might be made of reinforced concrete or other material than wood, or my improved construction of rail fastening means might be used on a tie of standard dimensions, and hence I do not wish to be limited except by the prior art and the scope of the appended claims.

Having thus described my invention, what I claim as new and desire to secure by United States Letters Patent is:

1. A composite railway tie comprising a central portion of sufficient width to support an unjointed rail, side portions secured to said central portion at one end only, and extending therebeyond, whereby an enlarged bearing surface is formed at the said end adapted to support a rail joint, said central portion extending under both rails, but the extended side portions forming the necessary margin at the enlarged end, the overall length of the composite structure being that of a standard tie, whereby a notch is formed at the enlarged end between the projecting end portions, which permits ready tamping of the roadbed under the joint. 55

2. A built-up railway tie of the class described, comprising an elongated central wooden member of normal tie width, and two wooden block side members arranged one on each side of said central member at one end only thereof, and extending therebeyond, whereby an enlarged bearing surface is formed at the said end adapted to support a rail joint, said two side members having square inner ends whereby shoulders are formed which cooperate with the roadbed to prevent lateral shifting of the tie, said central member extending under both rails, but the extended side members forming the necessary margin at the enlarged end, the overall length of the composite structure being that of a standard tie, whereby a notch is formed at the enlarged end between the projecting side members which permits ready tamping of the roadbed under the joint. 80

In testimony whereof I hereunto affix my signature.

SAMUEL EDWARDS.
